(57) **CLAIM**

The ornamental design for a display board as shown and described.

DESCRIPTION

FIG. 1 is a perspective view of a display board, showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines represent portions of the display board that form no part of the claimed design. The shade lines in the Figures show contour and do not claim surface ornamentation or treatment.
